A. G. M. MICHELL

MECHANISM FOR THE INTERCONVERSION OF RECIPROCATING AND ROTARY MOTION

Filed Dec. 1, 1924

Inventor

Anthony G. M. Michell,
By Henry Groves Jr. Atty.

UNITED STATES PATENT OFFICE.

ANTHONY GEORGE MALDON MICHELL, OF MELBOURNE, VICTORIA, AUSTRALIA, AS
SIGNOR TO CRANKLESS ENGINES LIMITED, OF MELBOURNE, AUSTRALIA.

MECHANISM FOR THE INTERCONVERSION OF RECIPROCATING AND ROTARY MOTION.

Application filed December 1, 1924, Serial No. 753,308, and in Australia July 18, 1924.

This invention relates to an improved mechanism of the type in which a reciprocating member actuates, or is actuated by, a rotating element in the form of a swash plate or slant, coaction between said member and element being effected by means of a pair of slippers quaquaversally articulated to the reciprocating member, that is to say, to mechanism of the type described in the specification of Reissue Patent No. 15,756. The improvement relates more especially to the forms of such mechanism in which the reciprocating member is unsymmetrical on the two sides of the slant, for example to constructions similar to that illustrated in Fig. 8, of the cited patent, and it will be hereinafter described and illustrated as applied to such a construction.

In machines of the type described in the above-mentioned patent, the reciprocating member has imposed upon it by the slippers, lateral forces which are resisted by the parts of the mechanism which guide such reciprocating member.

It is the principal object of the present invention to provide means for guiding the reciprocating member in such a manner that the guiding surfaces may be independent of piston elements or the like parts of such reciprocating elements, and consequently may be thoroughly lubricated, and that such surfaces may effectively support the lateral pressures transmitted from the slippers. These lateral pressures act, in various phases of motion of the type of mechanism in question, in all directions radially from the axis of the reciprocating member, and it is consequently the aim of the present invention to provide effective support for the lateral pressure, in whichever direction it may be momentarily acting.

In the accompanying drawings, Fig. 1 is a longitudinal section on a plane passing through the axes of both the reciprocating and the rotary elements; Fig. 2 is a cross-section on line II, II of Fig. 1; Fig. 3 is a section on the same plane as Fig. 1, showing parts of the mechanism in a different phase of the motion. For the sake of clearness, moving parts shown in section are hatched, while stationary parts are left in outline.

As shown in Fig. 1, the swash-plate or slant 1, has the form of an annulus with concentric cylindrical inner and outer surfaces, 2, 3, and plane and parallel lateral surfaces,

4, 5, the planes of these latter surfaces being oblique to the axis A A of the main shaft 2^a. In other words the slant 1 may be described as an oblique parallel section, or slice, of a hollow cylinder, the surfaces 2, 3, being portions of the inner and outer surfaces of the cylinder. The slant 1 is mounted on a cylindrical rim 6, which may be integral with or secured to the slant, and a web member 10. The rim 6 may be constructed in one piece with the web 10, or may be attached thereto as by bolts 11. The web 10, with its boss 9, may likewise be integral with, or attached by well known means to the main shaft 2^a, which thus rotates with the slant. 60

The reciprocating member which may consist of a piston 13, piston stem 14, and yoke 15, is furnished with two slippers 16, 17, which are articulated to the yoke 15, in such manner that their respective plane 75 working surfaces 18, 19, make contact respectively with the plane surfaces 4, 5, of the slant 1, in all the positions assumed by the latter during its rotation.

For a description of the construction of 80 the slippers 16, 17, reference may be made to the specification of the patent above cited.

The yoke 15, besides being the means of connecting the supports of the slippers 16 and 17, serves also as a means of guiding the motion of the reciprocating member. For this purpose it is fitted with bearing surfaces 20, 21, parallel to the axis a, a, of the reciprocating member. These surfaces may preferably be portions of a common cylindrical surface, (as indicated in Fig. 2) co-axial with the cylinder 23, in which the piston 13 reciprocates, and in such case the bearing surfaces 20, 21, of the yoke, slide respectively on corresponding fixed surfaces 90 24, 25, which likewise form portions of a common cylinder. The surfaces 24, 25, may be formed on guide members consisting of integral extensions 27, 28, from the front wall of the cylinder 23, as indicated in Fig. 1, or may be upon separate members fixed relatively to the said cylinder by any known means.

As will be seen from Fig. 2, the members 27, 28, are separated from one another in the radial direction by a circumferential gap, this gap being necessary to admit the slant 1 and a portion of the rim 6, when in the positions shown in Fig. 1. 100

It will be understood that, as shown in Fig. 1, the reciprocating member is at the 110

left-hand end of its stroke. The positions of the principal parts of the yoke, relatively to the slant 1, and to the guide members 27, 28, when the reciprocating member is at the 5 opposite, or right-hand end of its stroke, are indicated in Fig. 3, from which it will be seen that the surfaces 24, 25, of the guide-members 27, 28, effectively guide the surfaces 20, 21, of the yoke when the piston is 10 in this extreme outward portion of its stroke, and that the special annular form of the slant 1, and cylindrical form of the rim 6, are adapted to admit of the use of such guide surfaces and members. It will be understood that the 15 construction of the piston, piston-stem, and yoke in separate pieces, as above described and illustrated, is not an essential feature of the invention, as these parts may be constructed and connected in a variety of other ways which are well known or will be readily apparent to the designers of machines. Similarly, the slant 1, and rim 6, instead of 20 being constructed separately from, and detachably connected to the web 10 as shown, may be formed integrally therewith, or the web 10 may be formed integrally with the rim 6, and the slant 1 may be detachably 25 mounted on the latter or all three parts 30 may be made as separate elements. A detachable connection between the parts has the advantage that by breaking a joint such as 29 in the main casing, 30, 30^a, of the machine and at the same time detaching the slant 1, the whole of that portion of the engine-casing 30, comprising cylinders, pistons, 35 yokes and slant, may be drawn off longitudinally with the bearing 31, leaving the rear portion 30^a of the casing, with the shaft 40 in position in its bearing 32.

It will be understood that the oblique slant 1, and unsymmetrical rim 6, are susceptible of the same kind of dynamical balance by means of the reciprocating parts as 45 is explained in the prior patent Reissue 15,756. It being necessary that the rotating member, including the said rim 6, shall be statically balanced about the axis A, A, the unsymmetrical form of the rim 6, may 50 for this purpose be compensated for by forming holes as 33 in the wider portion of the rim, as well as holes 34 in the web 10, adjacent to said wider portion of the rim.

Alternatively this balance may be effected by adding balance weights to the rotating 55 parts, in any of various well known ways.

Lubrication of the mechanism hereinbefore described may be effected by any method usually applied to slant and slipper mechanisms, e. g. jets of oil may be directed, from 60 nozzles supplied under pressure or by means of injectors supplied with compressed air, upon the working faces 4, 5, of the annular slant, and additional jets may be directed upon the working surfaces 24, 25. Alternatively lubrication of the slant and slipper mechanism may be effected, by delivering 65 oil upon the inner surface of the rotating cylindrical rim 6, such oil being retained upon and distributed over the said surface 70 by centrifugal force and thence delivered at the open end of the said rim to the surface 5, of the annular slant 1.

I claim:—

1. In mechanism for the interconversion of reciprocating and rotary motion, a reciprocating piston member, an annular swash plate, slippers on said member engaging with the swash plate, longitudinal guide members on the reciprocating member and adjacent the slippers, and stationary longitudinal guide members co-acting with the 80 guide members on the reciprocating member.

2. In mechanism for the interconversion of reciprocating and rotary motion, a reciprocating member, slippers thereon, an annular swash plate, a pair of guides on said member adjacent the slippers, and stationary elements on which said guides slide, said guides arranged respectively exterior and 90 interior of said swash plate.

3. In mechanism for the interconversion of reciprocating and rotary motion, a reciprocating member, slippers thereon, an annular swash plate, a pair of cylindrical guides on said member adjacent the slippers, and stationary cylindrical elements on which 95 said guides slide, said guides arranged respectively exterior and interior of said swash plate.

Dated this thirtieth day of September, 1924.

ANTHONY GEORGE MALDON MICHELL.
